UNITED STATES PATENT OFFICE.

ARTHUR REMY FREDERICKS, OF LOS ANGELES, CALIFORNIA.

METHOD OF STAGE SETTING AND APPARATUS THEREFOR.

Application filed March 4, 1922. Serial No. 541,257.

To all whom it may concern:

Be it known that I, ARTHUR R. FREDERICKS, a citizen of the United States, residing at Los Angeles, county of Los Angeles, and State of California, have invented new and useful Improvements in Methods of Stage Setting and Apparatus Therefor, of which the following is a specification.

10 This invention relates to a method of stage setting and an apparatus therefor.

It is common practice to effect a number of complete changes in scenery on a stage during the course of a dramatic or like production to represent the different scenes of action in which the play is laid. The method and apparatus generally employed to accomplish the change in scenery has in some instances been found unsatisfactory due to 15 the fact that it not only requires considerable time and labor to complete the shift and change the scenes, but it also requires a complete set of new scenes for each setting. In view of these objections, it is the object 20 of the present invention to provide a method and apparatus for setting the stages whereby a number of changes in formation, color variations and scenic effects may be readily and quickly effected by manipulation of a 25 scene set of suspended and adjustable panels.

30 The invention more specifically stated contemplates the arranging and supporting of a plurality of cables directly below the stage ceiling, from which cables are suspended a plurality of panel supporting devices, said devices being capable of movement longitudinally of the cables and being adjustable both vertically and angularly with relation to the stage; the said devices 35 also being movable in relation to each other so as to permit arranging of the scenery and various formations and color combinations. One form which the invention may 40 assume is exemplified in the following description, and illustrated by way of example in the accompanying drawings, in which—

45 Fig. 1 is a schematic or diagrammatic view illustrating in plan one of the several forms of setting which may be effected by 50 use of the present method and apparatus.

Fig. 2 is a perspective view disclosing the manner in which a combination setting in colors or scenic effect may be obtained.

55 Fig. 3 is a front view of one of the panel supporting devices.

Fig. 4 is a cross section taken on line 4—4, Fig. 3.

Fig. 5 is a vertical section taken on line 5—5, Fig. 3.

Referring to the drawings in detail, and particularly to Fig. 1, A indicates a theatrical or like stage having a proscenium arch 10, a front drop curtain 11, and one or more rear drop curtains, as indicated at 12. Arranged transversely of the stage and the proscenium arch, and secured directly beneath the ceiling of the stage is a plurality of cables 13. These cables are preferably arranged in parallelism and interspaced and may be secured in any suitable manner to obtain the desired degree of tautness or tension. Supported by and suspended from each cable is a number of panel or curtain supporting devices which will hereinafter be referred to as bridles. These bridles are adapted to support the respective panels or curtains employed as indicated at 15. The specific construction of the respective bridles is more particularly illustrated in Figs. 3, 4 and 5. It consists of a carriage 16, which is suspended from the cables by means of eye-bolts 17, said eye bolts permitting longitudinal movement of the carriages along the cables or crosswise of the stage. Secured centrally of the carriage and extending downwardly therefrom is a forked bracket member 18, to which is pivotally attached a rod 19, said rod due to the pivotal attachment will always assume a vertical position and serves as a support for 50 the bridle proper indicated at 20. Slidably and turnably mounted on the rod is a head member 21, on which is formed a pair of bearing members as indicated at 21^a. The bridle proper is secured to the head member 21 in any suitable manner or as here indicated and as such permits vertical and turning movement on the bridle with relation to the rod. The bridle, as previously stated, forms a support for the panel or hanging 55 attached thereto and to render such attachment convenient eyelets 21^b are arranged along the lower edge. Means are provided for the purpose of securing the bridles against vertical and turning movement 60 about the rod, and this is accomplished in the following manner:

Formed intermediate the bearing sections 21^a of the head or plate member 21 is a pair of guide brackets 27, and slidably mounted 65

110

between said brackets is a carriage or clamping member 25, one end of said carriage being attached to a coil spring 28, while the opposite end is attached to a cable 29 as shown. 5 The carriage or clamping member 25 is adapted to engage one side of the rod 19 as shown in Figs. 3 and 4, and as such produces a friction grip which is sufficient to retain the bridle against vertical movement 10 when adjusted on the rod and against turning movement thereon.

For the purpose of imparting vertical movement to the bridle, a cable 23 is provided. One end of the cable is attached to the upper end of the bridle as indicated at 15 29^a; it is then passed over a pulley 22 carried in the bracket member 18 and is then extended to the lower end of the panel where it is suspended. In fact both cables 23 and 20 29 are freely suspended behind the bridle and panel carried thereby as shown in Fig. 3 so that they may be conveniently grasped when it is desired to adjust the position of a particular panel. If it is desired to turn 25 the bridle and panel so as to swing them to an angular position with relation to the stage and the cables supporting the same as indicated at 14, in Fig. 1, it is accomplished by merely grasping the panel and 30 imparting a turning movement thereto. If it is desired to raise or lower the bridle and panel upon the rod it is accomplished by grasping the cables 23 and 29 and exerting a pull thereon; for instance a pull exerted 35 on the cable 29 will release the clamp with relation to the rod and will thus permit free vertical movement of the bridle and panel upon the rod. If it is desired to raise the panel, it is accomplished by exerting a pull 40 on the cable 23. If it is desired to lower the bridle and panel, it is accomplished by paying out on the cable 23. When the desired position is assumed, it is only necessary to relieve the pull or tension on the cable 29, 45 thus permitting the spring 28 to pull the clamp into frictional engagement with the rod and thereby lock the bridle and panel against further movement. Again, if it is desired to move a certain panel along the 50 cable supporting the same, it is only necessary to grasp the edge of the panel and the cable 23 and to exert a pull in the direction desired. A pull thus exerted will cause the carriage 16 to slide along the cable and it may thus be moved to any position desired.

The number of cables required on a certain stage depends entirely upon the extent of equipment necessary or wanted. Also, 60 the depth of the stage determines the number of cables or bridles employed. A setting can consist of a right and a left wing, and one or more back curtains, as depth effect may require, see Fig. 1. If a single setting is required, only one set of curtains or panels

will be employed. If a double setting is wanted, two sets of panels are employed, and if a more extensive equipment is required, three or more sets of panels may be employed. For a stage with a high ceiling, 70 the wings can be raised one over the other to a desired height, or they may be raised completely out of sight or vision. Again, it is obvious that they can be lowered to the stage floor and then shifted to any position 75 or angle required, thereby condensing the size of the stage and also permitting complete clearing of the stage if desired. The back curtains are naturally designed to conform to the side wings and will therefore 80 assist in carrying out the same effect. Where a low ceiling is employed, all adjustments may be had as previously stated, except that vertical adjustment of the panels will be more or less limited. Where a set- 85 ting of three or more panels is wanted, the panels should be hung or spaced about nine inches apart. This will allow plenty of clearance. For instance if one setting or 90 set of panels is colored red, another set colored blue, and a third set colored tan, a setting or effect can be secured with a tan wainscot, a blue side wall above the wainscot and a red frieze also obtained, or a red curtain effect may be obtained with a blue border 95 down the side and across the bottom, or a tan border and a blue curtain effect may be obtained; all of the various changes being secured by moving one curtain forward of the other and raising and lowering the 100 same to obtain the effect desired. The wings can be turned to any angle, as shown at 14 in Fig. 1, to form a box like setting or circular effect as the friction lock employed on the respective bridles will secure the curtains in any position desired; the tension on the springs 28 being adjusted or gauged to the required weight so as to support the curtains against vertical and turning movement 105 when adjusted.

From the foregoing it can be seen that numerous stage settings, color effects and scenic displays may be obtained with a pre-determined number of panels, and that such changes may be readily and quickly effected. 110

While certain features of the present invention are more or less specifically illustrated, I wish it understood that various changes in form and proportion may be resorted to within the scope of the appended 115 claims, similarly that the materials and finish of the several parts employed may be such as the experience and judgment of the manufacturer may dictate or various uses may demand.

Having thus described my invention, what I claim and desire to secure by Letters Patent is—

1. In combination with a stage having cables arranged and supported adjacent the 120

- ceiling thereof, of a suspension member adapted to support a panel, said suspension member comprising a carriage adapted to travel along the cable, a downwardly extending member pivotally connected to said carriage, a panel carrying bridle turnably and slidably mounted on said downwardly extending member, and means for locking the bridle against movement thereon.
- 5 2. In combination with a stage having cables arranged and supported adjacent the ceiling of the stage, of a suspension member comprising a carriage adapted to slidably engage a cable, a downwardly extending rod pivotally connected to said carriage, a bridle member turnably and slidably mounted on said rod, a friction clamp carried by the bridle and adapted to normally engage said rod, and means for releasing said clamp.
- 10 3. The combination with the proscenium arch and the ceiling of a stage, of a series of spaced supporting members secured adjacent the ceiling and disposed crosswise of the proscenium arch, a carrier movable along each support, a panel suspended from each carrier, means disposed in line with the vertical axis of each panel to permit turning movement of the panel about its vertical axis, and means whereby to vertically adjust each panel along the respective aforesaid means.
- 15 4. In combination with a stage having cables arranged and supported adjacent to the ceiling, a carrier slidable on each cable, means for supporting a panel on each cable, means whereby to adjust the panel toward and away from said supporting means, means whereby to permit of angular adjustment of each panel, a lock normally holding the panel against the aforesaid adjustments, and means connected with the aforesaid locking means whereby to release the latter.
- 20 5. A stage setting apparatus comprising a plurality of spaced groups of cables adjacent the ceiling of the stage and extending parallel across the same, a carriage slidably mounted on each cable, a bridle member supported by the carriage for vertical and angular adjustment, and panels secured to each bridle and adjustable therewith to produce variations in scenic effects.
- 25 6. A stage setting apparatus comprising a plurality of equally spaced groups of cables adjacent the ceiling of a stage, a carriage slidably mounted on each cable for longitudinal adjustment, a bridle carried by the carriage for vertical and angular adjustment and panels depending from each bridle, the said groups of cables being so spaced that the panels will overlap when adjusted to angular position, thereby producing the appearance of a continuous wall.
- 30 7. A stage setting apparatus comprising a plurality of cables adjacent the ceiling of a stage, a carriage slidably mounted on each cable for longitudinal adjustment, a bridle supported by the carriage for vertical and angular adjustment, a lock for the bridle normally holding the same against movement, means operable from the stage for effecting adjustment of the bridles and other means operable from the stage for releasing the bridle lock.
- 35 8. A stage setting apparatus comprising a plurality of cables adjacent the ceiling of a stage, a carriage slidably mounted on each cable, a downwardly extending rod connected to the carriage, a bridle turnably and slidably mounted on the rod, a lock for the bridle comprising a slidable clamping member, and a spring for normally urging the clamping member into engagement with the rod.
- 40 9. A stage setting apparatus comprising a plurality of cables adjacent the ceiling of a stage, a carriage slidable on each cable, a rod depending from each carriage, and a head member turnably and slidably mounted on the rod, the said head member comprising spaced bearings for the rod and an intermediate guideway, a clamping member slidable in the guideway and normally engaging the rod to hold the head member against movement, and a panel supporting the bridle on the head member.

ARTHUR REMY FREDERICKS.
